Specification for Design.

Patented Apr. 26, 1921.

Application filed June 19, 1920. Serial No. 390,265. Term of patent 7 years.

To all whom it may concern:

Be it known that I, FRANÇOIS RICHARD, a citizen of the French Republic, residing at 7800 Finney Ave., in the city of Cleveland, county of Cuyahoga, and State of Ohio, have invented a new, original, and ornamental Design for a Wheel, of which the following is a specification, reference being had to the accompanying drawing, forming part thereof.

Figure I is a front view of a wheel showing my new design.

Fig. II is a back view thereof.

I claim:

The ornamental design for a wheel as shown.

FRANÇOIS RICHARD.
